UNITED STATES PATENT OFFICE.

JOHANN FRANZ EDUARD WOLDEMAR SCHMIDT, OF DRESDEN, SAXONY,
GERMANY.

REGENERATIVE-LAMP.

SPECIFICATION forming part of Letters Patent No. 408,197, dated July 30, 1889.

Application filed January 21, 1889. Serial No. 297,031. (No model.) Patented in England December 11, 1888, No. 18,066; in Switzerland December 15, 1888, No. 184; in France December 17, 1888, No. 194,818; in Belgium December 17, 1888, No. 84,316; in Spain December 21, 1888, No. 9,020; in Italy December 31, 1888, No. 24,599, and in Denmark April 25, 1889, No. 1,266.

To all whom it may concern:

Be it known that I, JOHANN FRANZ EDUARD WOLDEMAR SCHMIDT, a citizen of Germany, residing at Dresden, Germany, have invented 5 certain new and useful Improvements in Regenerative Lamps, (for which I have obtained Letters Patent in Italy, No. 24,599, dated December 31, 1888; England, No. 18,066, dated December 11, 1888; Spain, No. 9,020, 10 dated December 21, 1888; France, No. 194,818, dated December 17, 1888; Belgium, No. 84,316, dated December 17, 1888; Switzerland, No. 184, dated December 15, 1888, and Denmark, No. 1,266, dated April 25, 1889,) of which the following is a full, clear, and exact specification:

This invention relates to that type of lamp having a burner and two globes wherein the light is radiated downward.

The object of my invention is to provide a novel 20 means whereby the circle of light is enlarged and softened, the ceiling is illuminated, and cool air admitted through an unobstructed orifice in the bottom of an external shade-globe is caused to ascend between the two 25 globes and escape at the open top of the external globe for carrying off the heat developed by the flame from a pendent burner.

The object of the invention is accomplished by the novel construction and combination of 30 devices hereinafter described and claimed, reference being made to the accompanying drawings, in which—

Figure 1 is a side elevation of part of a lamp showing my invention, the shade-globe and 35 its retaining-ring being in section. Fig. 2 is a similar view showing a variation in the configuration of the shade-globe. Fig. 3 is a detail plan view of the retaining-ring; and Fig. 4 is a sectional view of the same, taken through 40 the hinge of the ring-sections.

In order to enable those skilled in the art to make and use my invention, I will now describe the same in detail, referring to the drawings, wherein—

45 The letter A indicates an inverted pendent burner; d, a circular flange comprising part of the lamp-frame, and G the transparent burner-globe having imperforate bottom and

side walls, and in which the pendent burner hangs, all substantially as in the Wenham regenerative-burner lamps. The burner-globe G, suspended from the lamp-frame, as usual, is inclosed within a shade-globe M, composed of translucent vitreous material—such as milk-glass—and provided at its open top with 55 a laterally-projecting annular flange r and at the center of its bottom wall with a free or unobstructed air-inlet orifice O.

The shade-globe retaining-ring R is composed of two semicircular ring-sections united 60 at one end by a hinge or pivot c and detachably connected by a suitable catch h, so that the ring can be opened and closed to engage under the flange r of the shade-globe and thereby suspend it from the flange or lamp-frame D, through the medium of hooks s, secured to or formed with each ring-section, as shown in Fig. 1. Instead, however, of the ring engaging the flange r and the hooks catching over the flange or lamp-frame D, the 65 parts may be arranged as in Fig. 2, where the ring rests on the lamp-frame and the hooks engage the flange of the shade-globe.

The configuration of the shade-globe differs from that of the burner-globe, and the rays of 75 downwardly-radiated light are dispersed and the circle of light materially enlarged, while the ceiling is illuminated. The difference in configuration resides more particularly in the fact that the curved walls of the shade-globe 80 are eccentric to the imperforate curved walls of the burner-globe.

The shade-globe may have the form of a flattened ball, as in Fig. 1, or of a ball of spherical section, as in Fig. 2.

The orifice in the bottom of the shade-globe 85 constantly admits cool atmospheric air, and the entering air, absorbing the heat radiating from the burner-globe, creates an upward current that discharges through the open top 90 of the shade-globe, thereby causing a continuous circulation of air upward through the shade-globe to carry off the heat developed by the flame and keep the two globes comparatively cool. The form of the shade-globe is 95 such that by its laterally-expanded walls the

ceiling is illuminated, which in this type of lamps has not heretofore been accomplished. By my invention I provide a novel lamp having a pendent burner located in the trans-
5 parent burner-globe, the walls of which are imperforate, wherein the circle of downwardly-
radiating light is materially enlarged, the ceiling is illuminated, and the heat developed
by the flame is carried off by ascending cur-
10 rents of air constantly rising through the un-
obstructed opening in the shade-globe and
passing between the two globes out through
the open top of the exterior translucent globe.

By means of the retaining-ring the shade-
15 globe can be removed and replaced at will
whenever occasion requires.

Having thus described my invention, what I
claim is—

1. The combination of a lamp-frame, a
20 transparent burner-globe having imperforate
bottom and side walls and suspended from
the lamp-frame, a pendent burner in the
burner-globe, and a translucent shade-globe,
also suspended from the lamp-frame and in-
25 closing within it the burner-globe for enlarg-
ing the circle of downwardly-radiating light,
substantially as described.

2. The combination of a lamp-frame, a
pendent burner, a burner-globe suspended
30 from the lamp-frame, and a translucent shade-
globe suspended from the lamp-frame, inclos-
ing within it the burner-globe and having its

curved walls eccentric to the curved walls of
the burner-globe for enlarging the circle of
downwardly-radiating light, substantially as 35
described.

3. The combination, with a lamp-frame, a
burner-globe suspended therefrom and hav-
ing imperforate bottom and side walls, and a
pendent burner in the burner-globe, of the 40
translucent shade-globe, inclosing the burner-
globe and detachably connected at its open
top with the lamp-frame for enlarging the
circle of downwardly-radiating light, substan-
tially as described.

4. The combination of a lamp-frame, a
burner-globe suspended therefrom and hav-
ing imperforate bottom and side walls, a
pendent burner in the burner-globe, and a
translucent shade-globe suspended from the 50
lamp-frame, inclosing the burner-globe and
provided at its bottom with an unobstructed
air-inlet orifice for the constant admission of
ascending currents of cool air, which rise be-
tween the globes and discharge at the open 55
top of the shade-globe, substantially as de-
scribed.

In testimony whereof I affix my signature in
presence of two witnesses.

JOHANN FRANZ EDUARD WOLDEMAR SCHMIDT.
